DRAWER PULL

Norman D. Louis, Los Angeles, Calif., assignor to Ajax Hardware Manufacturing Corp., City of Industry, Calif., a corporation of California

Filed Sept. 4, 1962, Ser. No. 71,547

Term of patent 14 years

(Cl. D10—8)

FIG. 1.

FIG. 2.

FIG. 3.

FIG. 5

FIG. 4.

FIG. 1 is a front elevational view of a drawer pull showing my new design;

FIG. 2 is a bottom plan view thereof;

FIG. 3 is a top plan view thereof rotated 180° clockwise from the position shown in FIG. 2;

FIG. 4 is an end elevational view; and

FIG. 5 is an enlarged fragmentary sectional view taken along the line 5—5 in FIG. 1.

I claim:

The ornamental design for drawer pull, as shown.
